UNITED STATES PATENT OFFICE.

SOLON BISHOP, OF HOMER, NEW YORK.

WASHING-MACHINE.

Specification of Letters Patent No. 15,033, dated June 3, 1856.

To all whom it may concern:

Be it known that I, SOLON BISHOP, of Homer, in the county of Cortland and State of New York, have invented certain new and useful Improvements in Washing-Machines; and I do hereby declare that the following is a full, clear, and exact description of the same, reference being had to the accompanying drawings, making a part of this specification.

My improvement relates to that class of washing machines where a simple tub and vertical stem are employed as a guide in the movement of a floating disk or rubber. By the employment of a yoke placed or pivoted on the upper part of the stem in connection with a sliding disk I am enabled to shorten or reduce the height of the guide stem, so that while I give the necessary support to the disk at the varied heights it may necessarily assume in the tub, (by the quantity of clothes or water) I yet possess the decided advantage, not found in other machines, of being able to avoid the dropping of water, and splashing on the floor, in the removal of the disk from the stem, (caused by their great height), as well as facilitating the removal of said disk, in the hands of females usually employed, to whom the high lift is objectionable. By my low stem both of these objections are removed, and in the examination of the clothes the disk is simply raised and lodged in the tub. A further improvement is in providing the disk with ribs, combined with hemispherical projections, the ribs so situated that the clothes in the tub shall be changed in position by the action thereof, that is, they are thrown from the center, in turning the disk in one direction, and toward it, or reversing the movement of the disk.

To enable others to make and use my improvement I will proceed to describe it as follows.

A represents the tub, the bottom furnished with hemispherical knobs or projections (a) secured thereto. Their arrange-

ment resembling that of the disk, shown in Fig. 2.

B is a spindle whose extreme height does not exceed that of the tub; it is secured to the bottom of the tub by screw, wedge or otherwise; the stem is cylindrical at its upper end reduced in diameter, so that a shoulder (d) may be formed, on which the yoke G, rests. Said yoke freely turning on the spindle.

D is a disk fitting freely in the tub. The under side (as seen in Fig. 2) is provided with tangential ribs or bars (c) in combination with hemispherical knobs or knuckles (a) similar to those of the bottom of the tub A; E, E, uprights secured to the disk D; they pass freely through the yoke, and are connected at their upper ends by a handle H: In the removal of the disk, the yoke is taken off therewith from the spindle.

This machine may be furnished at a small expense, compared with others, and being simple and compact, occupies no more room, and as it resembles a wash tub, is not more liable to be out of order.

The clothes to be washed are placed in the tub, with the requisite water or soap suds, the disk is slipped on the spindle, and the yoke rests on the shoulder at the top thereof. A reciprocatory movement is given the disk by the handle H, in which movement the yoke G, gives steadiness to it, at all heights of the disk.

Having described my improvement what I claim as my invention and desire to secure by Letters Patent is—

The use of the yoke G, in combination with the spindle B, and uprights E, E, for giving steadiness to the disk D, substantially as described.

In testimony whereof I have hereunto signed my name before two subscribing witnesses.

SOLON BISHOP.
